HIGH FREQUENCY MAGNETRON AMPLIFIER

Ernest G. Linder, Philadelphia, Pa., assignor to
Radio Corporation of America, a corporation
of Delaware

Application December 31, 1935, Serial No. 56,890

12 Claims. (Cl. 179—171)

My invention relates to amplifiers for high frequency currents. More specifically my invention is a push pull magnetron amplifier for amplifying currents at ultra high frequencies.

Amplification of ultra high frequency currents with conventional types of thermionic tubes offers numerous difficulties. These difficulties are primarily the result of the interelectrode capacities of the tubes. My invention contemplates the use of magnetron tubes in which the electron path is varied to effect amplification.

One of the objects of my invention is to amplify ultra high frequency currents by varying the electron path within a magnetron.

Another object is found in the means for effecting push pull amplification of ultra high frequency currents.

A further object is the design of a magnetron amplifier having four positively biased electrodes which are operated as oppositely arranged pairs.

Additional objects will appear in the accompanying specification and appended claims.

An understanding of my invention may best be had by referring to the accompanying drawing in which,

Figure I is a schematic drawing representing a magnetron embodying one arrangement of my invention.

Fig. Ia is a perspective view of the electrodes of Fig. I,

Fig. II is a schematic circuit diagram showing an embodiment of my invention.

Fig. III is a schematic illustration of a suitable circuit for push pull amplification at ultra high frequencies.

Fig. IV is drawing used to illustrate the mode of operation of the magnetron amplifier of my invention operating near the cut-off point, and

Fig. V is a graph or characteristic curve illustrating the relation between input voltages and output currents of a push pull magnetron amplifier.

In Fig. I within an evacuated envelope 1 are arranged three pairs of lead wires. One of these pairs 3-5 support a filament 7. The second pair of lead wires 9-11 support a pair of cylindrical shape anodes 13-15. The remaining pair of wires 17-19 support a second pair of cylindrical shape electrodes 21-23.

These anodes are preferably made from a cylinder which has been divided into sections each having an angular width equal to slightly less than a quadrant. These sections, by way of example, may have a length about twice that of their width. The space between the cylindrical

sections is substantially less than that of their widths and is of the order of 1°-15° hereinafter called θ . The radius of the cylinder formed by the quadrants is of the order of one half centimeter, by way of example.

The filament is slightly longer than the anodes and is arranged substantially on the axis of the cylinder formed by the anode electrodes as shown in Fig. Ia. It should be understood that suitably insulated supports may be used within the envelope to maintain the filament and anode electrodes in their proper positions.

The operation of a magnetron contemplates a magnetic field whose lines of force are substantially parallel with the axis of the anodes. This field may be generated by an electromagnet whose magnetic core 25 may be energized by a suitable field winding 27. The magnetic field may be varied by adjustments of the magnetizing currents.

A perspective view of the electrodes is presented in Fig. Ia. In this figure and throughout the specification, similar parts of the several figures will be represented by similar reference numerals. In Fig. Ia, the magnetic field and evacuated envelope are omitted for simplicity of illustration.

In Fig. II the anodes 13-15 have been connected through the lead wires 9-11 to a tunable tank circuit 29. This circuit is composed of a variable capacitor 31 and an inductor 33. The inductor 33 is coupled to the secondary 35 of an input circuit. The input circuit may be an antenna or the tank circuit 29 may serve as the antenna collector circuit.

The filament or cathode 7 is energized by a battery not illustrated. A biasing battery 37 has its negative terminal connected to cathode and its positive terminal is connected to a point intermediate the ends of inductor 33. This intermediate point is preferably the center of the inductor.

The anodes 21-23 are connected through the lead wires 17-19 to a tunable output tank circuit 39. The tank circuit is composed of a variable capacitor 41 and an inductor 43. A tap is made at the center of the inductor 43. This tap is connected to the positive terminal of a bias battery 45. The negative terminal of the bias battery 45 is connected to the filament 7. The tank circuit 39 is coupled to an output circuit 47 represented by the inductor 47. The output circuit may include additional amplifiers, detectors, or the like.

In practice the capacitor 31 and inductor 33, or the capacitor 41 and inductor 43, are not sep-

arate elements. One preferred form is to make a tank circuit as illustrated in Fig. III. In this figure the lead wires 9-11 are slipped within a U shape tubular member 49. The electrical length 5 of the circuit may be adjusted by sliding the U shape member 49 on the lead wires 9-11. The wires and the U shape member have both capacitance and inductance which is sufficient to tune the tank circuit throughout a range of ultra high 10 frequencies. A similar U shape member 51 is adjusted on lead wires 17-19.

Biassing batteries 53-55 are respectively connected to the centers of the U shape members 49-51. The potential of the two batteries may 15 be adjusted to obtain optimum amplification. In general the bias applied to the input electrodes is less positive than the bias of the output electrodes. The negative terminals of these biassing batteries are connected to the cathode 7. In Figs. II and 20 III the magnetic fields have been illustrated by a circle and an appropriate legend to simplify the drawing. It should be understood that magnetic fields are employed in each case. Likewise positively charged end plates may be used to establish 25 a suitable electrostatic field with a component of its lines of force parallel to the cathode or filament 7. The magnetic fields are used with the magnetrons employing end plates.

Having described the magnetron tube and associated 30 circuits, I shall now explain the operation of the amplifier, without limiting my invention to the precise theory set forth. In Figure IV the positively biased electrodes are represented as 35 13, 15, 21 and 23. In the absence of a magnetic field, electrons emitted from the cathode 7 will normally move in a straight line path from the cathode 7 to the positive electrodes 13, 15, 21 and 23. If, however, a magnetic field is applied, whose lines of force are perpendicular to the plane of the 40 paper, the electrons emitted from the cathode 7 will traverse curvilinear paths such as represented by 51. The magnetic field—and if end plates are used, the electrostatic field—and the biasing potentials are each adjusted until a critical cut-off 45 characteristic is reached or exceeded.

At or beyond the critical value the electron paths near the anodes are almost tangent to the anodes. Under this condition, if a radio frequency current is set up in the input tank circuit, 50 the flow of current in the tank circuit will alternately apply positive charges to one anode and negative charges to the other anode, said anodes being connected to the circuit. The potential difference arising from these charges will increase 55 the number of electrons flowing to one of the output anodes and decrease the number flowing to the other output anode.

The increased number of electrons arises from the increase in the force acting on electrons leaving the cathode 7 and moving toward the more positive of the input quadrants 13. Due to the increased force, the electron velocity is increased. Since the magnetic field is constant it will have less effect on the electrons moving at higher 65 velocity and the paths described by the electrons become of greater radius whereby larger numbers of electrons impinge on the output quadrant 23 because smaller numbers of electrons are tangent to the electrode 23.

70 Conversely, for the more negative, or less positive input electrode 15, the velocity of approaching electrons is decreased, the paths become smaller in radius, and fewer electrons impinge upon the output quadrant 21. When the input 75 currents reverse in sign, the above described ac-

tion takes place between oppositely arranged pairs of electrodes; i. e., electrode 15 takes the place of electrode 13, and electrode 21 takes the place of electrode 23. The simultaneous increased and decreased electron flow is equivalent to push pull 5 operation.

These results are obtained when the electron revolves around the cathode through an angle of not less than θ or more than $180^\circ - \theta$ as measured from the point of emission of said electron and to the point at which said electron impinges on one of said anodes. The required angular path is obtained by the design of the anode radius, the cathode radius, and the normal operating space charge. The limits of angular rotation of the 15 electron path are not critical. I have found that magnetrons whose cathode radius is small with respect to the anode radius, and whose space charge effect is negligible, will have electron paths whose angle of rotation falls within the pre- 20 scribed limits. If magnetic fields greatly exceeding the critical cut-off value are employed, the exact path followed by the electrons will differ from the curve 51 of Fig. IV but the net angular rotation of the path about the cathode will be 25 within the prescribed limits.

The characteristic curves of input voltage plotted against output currents appear in Fig. V. If the operation is maintained between the points 30 *a* and *b* on the curve *c* by proper adjustment of the magnetic field, the amplification is substantially linear.

It is evident that when the quadrants are of equal shape and size, and are symmetrically arranged, as shown in the drawing, the capacity between adjacent quadrants will be uniform. Since alternate oppositely disposed pairs are connected in push-pull, equal and oppositely phased voltages will be induced in each output quadrant by the two input quadrants. Consequently, the net result is a complete neutralization of the effect of interelectrode capacity between input and output electrodes. 35

The foregoing specification and drawing are merely illustrative of my invention. Numerous 45 modifications within the scope of my invention will occur to those skilled in the art. It should be understood that my invention is only limited as required by the prior art and appended claims.

I claim as my invention:

1. A magnetron amplifier having a cathode and four anodes; said anodes being symmetrically arranged about said cathode, substantially parallel thereto, and separated from each other; an input circuit connected to a pair of said anodes oppositely disposed about said cathode; an output circuit connected to the remaining oppositely disposed pair of anodes; and a magnetic field whose lines of force are substantially parallel with said cathode. 60

2. A magnetron amplifier having a cathode and four anodes; said anodes being symmetrically arranged about said cathode, substantially parallel thereto, and separated from each other; an input circuit connected to a pair of said anodes oppositely disposed about said cathode; an output circuit connected to the remaining oppositely disposed pair of anodes; a magnetic field whose lines of force are substantially parallel with said cathode, and means for positively biasing at least 65 one of said pair of anodes with respect to said cathode.

3. In a device of the character of claim 2, a pair of end plates whose planes are substantially perpendicular to said cathode, and means 70 75

for biasing said end plates positively with respect to said cathode.

4. A magnetron amplifier having a cathode and four anodes; said anodes being symmetrical-
5 ly arranged about said cathode, substantially parallel thereto, and separated from each other; an input circuit connected to a pair of said anodes oppositely disposed about said cathode; an output circuit connected to the remaining 10 oppositely disposed pair of anodes; a magnetic field whose lines of force are substantially parallel with said cathode and means for applying positive potentials to said pairs of anodes with respect to said cathode.

15 5. An ultra high frequency amplifier comprising an evacuated envelope; an electron emitting cathode, four electrodes having curved surfaces, said surfaces being slightly less than 90° in width, concentrically disposed about said cathode and within said envelope; an input circuit connected to two oppositely disposed electrodes; an output circuit connected to the remaining electrodes; means for biasing said electrodes positively with respect to said cathode; and 20 means for causing electrons to follow curvilinear paths as the electrons travel from the cathode toward said electrodes.

6. An ultra high frequency amplifier comprising an evacuated envelope; an electron emitting cathode, four anodes of partial cylindrical shape, each separated from the other by spaces equal to angles of θ° and concentrically disposed about said cathode and within said envelope; an input circuit connected to an oppositely disposed 30 pair of said anodes; means revolving electrons about said cathode through an angle of more than θ° and less than $180^\circ - \theta^\circ$; and means including said anodes for increasing the number of electrons impinging on one anode of the other of said pair of anodes and for decreasing 35 the number of electrons impinging on the anode oppositely disposed to said last mentioned anode whereby the numbers of electrons reaching said anodes may be respectively increased and decreased to effect amplification of 40 currents applied to said input circuit.

7. In a device of the character of claim 6 a tunable input circuit connected in push-pull relation to two of said anodes, and a tunable output circuit connected in push-pull relation to 50 the remaining two anodes.

8. In a high frequency amplifier circuit, an electron discharge tube having a cathode and a plurality of pairs of separate anodes, said anodes being of partial cylindrical shape and 55 concentrically arranged to form a cylinder about said cathode, the anodes of each pair being diametrically opposed, means for producing a magnetic field substantially coaxial with respect to the system of said cathode and said anodes, means for applying to one pair of oppositely disposed anodes a direct current potential which is positive with respect to the potential of said cathode, means for applying to a second pair 60 of said anodes a direct current potential which is positive with respect to the potential of the first said anodes, means for impressing an alternating potential in a push-pull manner upon the first said anodes with respect to said cathode, thereby to provide, in cooperation with 65

the magnetic field, a control of the electronic emission from said cathode, and means including the more positively charged anodes for deriving amplified alternating output currents the frequency of which is determined by said control of the electronic emission. 5

9. In a high frequency push-pull amplifier, a magnetron discharge tube having four anode segments of cylindrical contour and a centrally disposed cathode, means for applying a controlling alternating voltage to two opposite anode segments thereby to control the distribution of electronic flow radially from said cathode, means for producing a magnetic field in the region of said flow and having lines of force lying at an angle which approaches 90° with respect to the direction of said electronic flow and means including two other oppositely disposed anode segments charged to a more positive potential than that of the first said anode segments for deriving a useful amplified alternating current the frequency characteristics of which are determined by those of said controlling alternating voltage acting upon said electronic flow. 15 20

10. In an alternating current amplifying device, an electron discharge tube having an electron emitting axial cathode and a plurality of anodes of equal size arranged in opposite pairs the surfaces of which have partial cylindrical form and are equi-distant from the axis of said cathode, means for producing a magnetic field which is substantially coaxial with said cathode, means for polarizing one pair of anodes positively with respect to said cathode and a second pair of anodes positively with respect to the first pair, means for impressing in a push-pull manner upon the first pair of anodes an alternating control voltage, and means including an output circuit connected in a push-pull manner to the anodes of said second pair for deriving a useful amplified alternating current. 25 30 35 40

11. The method of amplifying alternating currents in an electron discharge tube having a heated cathode and a plurality of anodes of partial cylindrical shape, the surfaces of which are equi-distant from said cathode and positively charged with respect thereto which consists in producing a flow of electrons within the region surrounded by said anodes, controlling the distribution of said flow to one pair of said anodes in dependence upon alternations of input energy applied in a push-pull manner to the anodes of another pair, and deflecting said flow away from the second said pair of anodes and toward said first pair in dependence upon the strength of a magnetic field in which said anodes and said cathode are immersed. 45 50 55

12. A high frequency amplifier circuit comprising an electron discharge tube having a cathode and a plurality of diametrically opposed anodes of partial cylindrical shape, the surfaces of which are equi-distant from said cathode, an input circuit connected between the cathode and one pair of opposed anodes, an output circuit connected between the cathode and a second pair of opposed anodes, and a source of magnetic field excitation arranged to be effective in the electron discharge zone of said tube. 60 65 70
